UNITED STATES PATENT OFFICE

161,216

WALLPAPER OR THE LIKE

James Seeman, Forest Hills, N. Y.

Application April 15, 1950, Serial No. 9,235

Term of patent 14 years

(Cl. D59—10)

To all whom it may concern:

Be it known that I, James Seeman, a citizen of the United States of America, residing in Forest Hills, county of Queens, and State of New York, have invented a new, original, and ornamental Design for a Wallpaper or the like, of which the following is a specification, reference being had to the accompanying drawing, forming part thereof.

The figure is a face view of a wallpaper or the like, showing my new design.

I claim:

The ornamental design for a wallpaper or the like, substantially as shown.

JAMES SEEMAN.
